UNITED STATES PATENT OFFICE.

HARRY H. OLSEN, OF MINNEAPOLIS, MINNESOTA.

TRAINMAN'S FLAG AND CONTAINER.

1,394,933.

Specification of Letters Patent. Patented Oct. 25, 1921.

Application filed June 18, 1917, Serial No. 176,638. Renewed February 28, 1921. Serial No. 448,336.

To all whom it may concern:

Be it known that I, HARRY H. OLSEN, a citizen of the United States, and a resident of Minneapolis, in the county of Hennepin 5 and State of Minnesota, have invented certain new and useful Improvements in a Trainman's Flag and Container, of which the following is a specification.

At the present time the laws for regulation 10 of interstate train service and the laws of various states require that a train man be sent back with a signal flag when a train is halted in variation with its schedule.

It is also required, in some instances, that 15 a trainman carry with him, not only a signal flag, but torpedoes, and at night he must carry a signal fusee.

Irrespective of the laws, however, for a proper safe guarding of human lives, the 20 trainman should carry with him whenever he is sent back for signaling, means for signaling under any possible condition that may arise, and it is often required that the flag man carry, not only a flag, but a fusee 25 and a pocket full of torpedoes, each and every time he is sent back on an unexpected stopping of a train.

My invention contemplates broadly the embodiment of a train man's flag, a fusee 30 container, a torpedo container, a supply of matches for lighting the fusee, and positive means for the ignition of safety matches, all combined into one device.

The invention furthermore contemplates 35 the use of a large handle adapted for slipping over the arm so that the trainman may use both hands in boarding a train.

One object of my invention is to provide 40 a flag and flag stick having means for readily detaching a flag from the stick for changing flags.

Another object of my invention is to provide 45 a flag stick in container form so as to carry therein a fusee.

Another object of invention is to provide 50 a flag stick in container form to carry therein one or more signal torpedoes.

Another object of my invention is to provide 55 in a container form of flagstick, means for carrying a supply of matches.

Another object of my invention is to provide 60 in a flag stick, carrying therein means for holding a supply of matches, means protected from the weather for striking safety 65 matches thereon.

Another object of my invention is to provide 60 in a container form of flag stick for fusees, means for preventing the spike of the fusee from puncturing the bottom of the container.

Another object of my invention is to provide 65 means for rendering weather proof, a container form of flag stick.

Another object of my invention is to provide 70 in a device of the class described, an enlarged carrying handle so the device may be carried on the arm.

With these and incidental objects in view, the invention consists of certain novel features of construction and combination of 70 parts, the essential elements of which are hereinafter described with reference to the drawing which accompanies and forms a part of this specification.

In the drawing, Figure 1 is an isometric 75 view of my improved trainman's flag and container; Fig. 2 is a conventional sectional view of the same; Fig. 3 is a section taken on the line 3-3, Fig. 2; and Fig. 4 is a section taken on the line 4-4, Fig. 2. 80

In my preferred construction the flag 1, Fig. 1, is attached by any suitable means to a wire 2, Fig. 3, adapted to slide into the receiving tube 3 having a slit aperture 4 running longitudinally thereof. 85

A cap 5, Fig. 2, preferably hinged to the fusee container 6 and closing thereon with a snap 7, closes not only the aperture of the fusee container but also the open end of the tube 3 so the wire 2, carrying flag 1, is held 90 securely in the slotted trough.

The fusee 8, Fig. 2, is of ordinary construction and fits the container 6, and a pair of lugs, 9, are provided in such fashion that the spike 10 of the fusee passes between 95 the lugs, but the lugs restrain any further motion of the fusee body.

Positioned concentrically about the fusee container 6 is a handle 11, a disk 12 serving to close the end of the fusee container 6 100 as well as to partition the container formed by the handle 11.

An annular chamber 13 is thus formed about the inner end of the fusee container 6 for the reception of the matches, preferably of the safety type, and a cover plate 14, slidably mounted in the handle 11, as shown in Fig. 1, allows access to the match chamber 13.

Below the partition 12 the handle provides 110

a container 15 for receiving signal torpedoes of ordinary and standard type, and the end of this container is closed by hinged cap 16 latchable with a snap 17, Fig. 1.

5 Hinged to the lower end of the handle 11 is curved plate 18 latchable in its closed position by wire 19 slid into engagement with a catch 20 and carrying on its inner surface 21 a chemical preparation of ordinary type for igniting thereon safety matches.

Securely fastened in any suitable hinged manner to ears 22 is a handle or bail 23 of sufficiently large diameter that it may 15 readily be carried over the trainman's arm so it is not necessary for him to carry the flag by the handle 11 on returning to board the train, but he can instead slip his arm through the enlarged handle 23 and have 20 both hands free to assist him in safely climbing aboard the train.

While I have described by invention and illustrated it in one design, I do not wish it understood that I limit myself to this 25 construction, as it is evident that my invention may be varied in many ways within the scope of the following claims.

Claims:

1. A container having a compartment for fusees, a compartment for signal torpedoes concentric therewith and carried thereby, a closure for the inner end of said fusee compartment closing also said signal torpedo compartment, forming on one side of said closure an annular space for matches and on the other side a chamber for signal torpedoes.

2. A container having a compartment for fusees and having thereon means for detachably connecting thereto a flag, an enlarged signal torpedo compartment carried by said fusee compartment and concentric therewith, a closure for the inner end of said fusee container dividing said signal torpedo compartment into an annular chamber for matches, and a cylindrical chamber for torpedoes.

3. A container having a compartment for fusees, means carried thereby for holding matches, means protected from the weather for striking safety matches thereon, and means for detachably connecting a flag stick to said container.

HARRY H. OLSEN.
